UNITED STATES PATENT OFFICE

GUSTAF L. FISK, OF PITTSBURGH, PENNSYLVANIA, ASSIGNOR TO MESTA MACHINE COMPANY, OF PITTSBURGH, PENNSYLVANIA, A CORPORATION OF PENNSYLVANIA

APPARATUS FOR CONVEYING AND SPRAYING MATERIAL

Application filed April 13, 1931. Serial No. 529,594.

The present invention relates broadly to the art of material handling, and more particularly to an improved conveyor system adapted especially for conveying hot metal strips, bars and the like.

In many cases in the art of metal working, it is desirable to produce a quasi-finished or intermediate product having a relatively clean surface. By clean surface I mean a surface relatively free from scale or the like.

It is well recognized in the art that in the hot rolling of metal, the metal leaves the rolls at such a temperature that scale is rapidly formed, the scale being an oxide of iron forming on the surface of the hot metal in contact with the oxygen of the air. It will therefore be apparent that the surface characteristics of the metal may be improved by keeping the metal out of contact with air during the cooling thereof. The present invention relates to an improved method and apparatus by means of which such air exclusion is effectively obtained.

It will further be apparent that the scale formation may be reduced by reducing the time interval during which the material is at a temperature high enough to form such an oxide. The present invention in addition to retaining the metal out of oxidizing contact with the air during the cooling period, also preferably contemplates means for expediting the cooling, whereby the time interval for oxidation is in itself reduced.

As one example of a material on which scale is particularly objectionable, reference may be made to sheet bars utilized for the formation of sheet material such as tin plate. If excessive scale is present on such sheet bars, the resulting product is obviously of inferior quality.

When it is considered that not infrequently sheet bars, which may vary in widths from approximately 8 inches to 24 inches; in thickness from $\frac{1}{8}$ of an inch or less to $1\frac{1}{2}$ inches or more and having lengths of approximately 30 feet, are customarily produced from a heated slab having approximately the width of the bar to be furnished and from 6 inches to 8 inches thick which is reduced by rolling under high temperature, the problems inci-

dent to the prevention of scale formation will be appreciated. Such slabs not infrequently weigh as much as 10,000 lbs. and when delivered by the last stand of rolls, may have a length up to 500 or 1000 ft. and speeds of 800 or more feet a minute.

Adjacent the finishing stand of the mill there is usually provided a flying shear effective for cutting the bar into the individual sheet bar lengths before referred to, these individual sheet bars being delivered to a conveyor effective for carrying the same from the shear to a piler. During travel along this conveyor, the individual sheet bars which are normally in free contact with the air tend to oxidize quickly whereby objectionable scale of the character referred to necessarily results. The present invention is hereinafter illustrated in connection with a conveyor of this character, although it will be understood that the utility of the invention is not limited either with respect to the particular type or constructional characteristics of the conveyor or to the sizes or character of the material being conveyed.

In the accompanying drawings, Figure 1 is a view partially in top plan and partially in section, being taken on the line I—I of Figure 2;

Figure 2 is a view partly in side elevation and partly in section of the conveyor illustrated in Figure 1, and taken along the line II—II of Figure 1; and

Figure 3 is a transverse sectional view along the line III—III of Figure 1.

It has heretofore been customary in the art to which this invention relates, to provide cooling means with certain types of conveyors. In the more primitive forms, such cooling means have comprised longitudinally extending pipe drilled to direct jets of water onto the material. Such pipes have usually only been located above the conveyor and have therefore not been effective for completely surrounding the material with a water film. They have further been so located as to interfere somewhat with easy access to the conveyor. In other cases, the cooling means has comprised a series of nozzles effective for projecting water jets in either a

vertical or a horizontal direction. With relatively narrow material, or when one section of material has passed over the jets, the water has been sprayed upwardly and away from the conveyor, thus giving a sloppy installation.

In other cases the material has been caused to travel between upper and lower spray members which, while satisfactorily performing the intended function, have been objectionable for the reason that they practically preclude access to the material on the conveyor without dismantling the installation. One of the objects of the present invention is to provide a construction which will effectively cool the material, maintain it surrounded by a non-oxidizing atmosphere, which will preclude any water discharge outside of the confines of the system itself, and will provide ready access to material on the conveyor and to the conveyor itself for inspection, repairs, etc., without dismantling the conveyor.

In the accompanying drawings there is shown a conveyor comprising side girders 2 and 3 held in the desired spaced and assembled relationship by means of suitable spreader, spacer and tie-bolt assemblies 4.

Extending transversely between the girders is a series of conveying rollers 5 of any desired construction and provided with suitable journals 6 as understood in the art. The shafts 7 carrying the rollers are illustrated as provided with bevel gears 8 meshing with similar gears 9 on a main shaft 10 extending longitudinally of the girder 3 and suitably journaled therein. This main shaft may be driven in any desired manner, as understood in the art, whereby all of the conveyor rollers may be simultaneously rotated in the desired direction for advancing material therealong. The individual rollers may each have a motor which will eliminate the bevel gears and main shaft.

Also extending transversely of the girders, and intermediate the rollers 5 are spray troughs 11. These spray troughs are herein illustrated as comprising a series of individual sections, each suitably secured in position and as being in the form of hollow castings each having an opening 12 adapted to align with similar openings 14 in the girders 2. This girder is likewise illustrated as being of hollow construction and as having an opening 15 by means of which it may be continuously supplied with water under suitable pressure.

With the parts assembled, the water will pass from the girder 2 into the body of the spray troughs 11 filling the bottom portion 16 thereof and the two sides portions 17. The bottom 16 is illustrated as being formed with a series of corrugations or ribs 18 having one or both sides thereof extending at an oblique angle to the supporting surface of the rollers 5. These inclined sides are formed

with perforations or openings 19 adapted to form jets 20 extending in a general upward and lateral direction, the angle of inclination of the jets being such that with no material on the rollers 5 the jets will impinge against the sides 17.

The inner walls 21 of the sides 17 are also illustrated as provided adjacent the upper portions with ribs or corrugations 22 providing oblique walls in which are formed openings 23. While these openings may be arranged in any desired manner, they are conveniently arranged in a series of inclined rows along lines such as the lines L of Figure 2. The inclination of these lines is preferably such that the uppermost jet in one line will be spaced from the lowermost jet in the preceding line by the horizontal distance between jets of the same line, although such an arrangement is not essential.

By drilling the individual jet openings in each line at slightly different angles, each line of openings will produce a sheet-like discharge which will gradually diverge so as to increase the area over which each line of jets is effective. The relationship of the openings in any case is such that the discharge from the two side walls will substantially completely cover the upper surface of any material being conveyed by the rollers 5.

In Figure 3, I have illustrated a piece of material M in position on the conveying rollers, it being obvious from this figure that the individual jets 20, which may be angularly disposed as described for the jets 24, are effective over the major portion of the lower surface of the material, while the jets 24 are effective over the major portion of the upper surface of the material. As the material travels onwardly, and thereby uncovers the jets 20, these jets will, by reason of their inclination as before described, impinge against the side walls 21, the corrugations 22 assisting in preventing the water from travelling upwardly along such side walls.

It is to be further observed that the openings 19 are located above the bottoms of the troughs 25 formed by the corrugations or ribs 18 and below the upper surfaces 26 of such ribs or corrugations. The upper surfaces 26 are likewise so disposed as to normally lie below the supporting plane of the rollers 5 in such manner as to normally be out of supporting engagement with the material M travelling over the rollers, although effective for engaging and supporting the material in the event of sagging thereof.

The sides 17 are also preferably formed at suitable intervals with inspection and clean out openings 27 normally closed by means of suitable cover plates 28.

By reason of the construction just described, it will be apparent that material passing over the conveyor is rapidly cooled to a temperature below that at which scale

will form. At the same time, the intimate contact effected by reason of the sprays between the material and the cooling water will cause the water to flash quickly into steam, thereby maintaining the material enveloped in a steam atmosphere effective for excluding air from contact therewith and thereby preventing an oxidizing atmosphere from reaching the material.

Not only is the obliquity of the jets 20 such as to maintain the water discharged thereby within the confines of the trough sections, but it is such as to effect a scouring action on the under surface of the material, a similar action being effected by the jets 24. Not only does the scouring action thus obtained tend to more effectively clean the surfaces of the material, but it tends to maintain a film of cooling water in intimate contact with the material, thereby more effectively accomplishing the desired cooling thereof.

In the event the material does sag onto the surface 26 as before described, it cannot close the openings 19 and the holes are therefore so located as to always permit a free discharge therefrom. The scale and dirt removed from the material by the scouring action above described will tend to collect in the troughs and be discharged from the trough sections adjacent the rollers 5. As before pointed out, however, the openings 19 are above the bottoms 20 of these troughs so that such a flow of water, scale, dirt and other impurities does not interfere with the desired jet formation.

The obliquity of the jets, by being of such nature that the unimpeded jets will impinge against parts of the trough structure, makes the apparatus self-contained and precludes the discharge of water over the sides of the spray troughs 11. This makes it unnecessary to provide any special covering means for the conveyor to interfere with the free accessibility to the conveyor parts and to the material thereon.

From the foregoing description taken in connection with the drawings forming a part of the present application, it will be apparent that material travelling along the conveyor is not only rapidly cooled to a temperature at which scale formation is prevented, but it is continuously maintained in a substantially oxygen-free atmosphere such that scale formation is prevented. This oxygen-free atmosphere is in turn provided by means effective for scouring and cleaning the material and thereby improving its surface characteristics. As will be further apparent, these desirable advantages are obtained in an open topped structure in which free accessibility may be had at all times to the material being conveyed.

While I have herein illustrated and described a preferred embodiment of the present invention, and have referred to the same

in connection with a particular type of material, it will be understood that the invention is not thus limited in scope, and that changes in the construction, characteristics and location of the parts may be made without departing either from the spirit of the invention or the scope of my broader claims.

I claim:

1. In a conveyor, supporting and conveying means, and a cooling trough intermediate said means and provided with corrugated bottom and side walls having jet openings therein, said cooling trough being entirely unobstructed throughout the length and width thereof in a plane above the bottom wall.

2. In a conveyor, supporting and conveying means, and cooling troughs intermediate said means and provided with corrugated bottom and side walls having inclined jet openings therein, the jet openings in the bottom wall being at such an inclination as to direct fluid discharged therefrom directly toward said side walls.

3. In a conveyor, supporting and conveying means, and a cooling trough intermediate said means, said trough being effective for delivering a plurality of opposed obliquely extending upwardly and downwardly directed jets onto the material carried by said conveying and supporting means, said cooling trough being entirely unobstructed throughout the length and width thereof in a plane above the bottom wall.

4. The combination with a conveyor comprising a series of rollers and means for driving said rollers, of hollow trough sections intermediate said rollers, and means for delivering cooling water to said trough sections, each of said sections having a plurality of inclined discharge openings directed substantially entirely toward the side walls of the trough sections.

5. The combination with a conveyor comprising a series of rollers and means for driving said rollers, of hollow trough sections intermediate said rollers and extending substantially the full distance between adjacent rollers, and a hollow supporting girder for said rollers for delivering cooling water to said trough sections, each of said sections having a plurality of inclined discharge openings.

6. The combination with a conveyor comprising a series of rollers and means for driving said rollers, of hollow trough sections intermediate said rollers having hollow bottom and side walls, and means for delivering cooling water to said hollow bottom and side walls, each of said trough sections having formed therein a plurality of obliquely extending openings.

7. The combination with a conveyor comprising a series of rollers and means for driving said rollers, of hollow trough sec-

tions intermediate said rollers and extending substantially the full distance between adjacent rollers and having hollow bottom and side walls, and means for delivering cooling water to said trough sections, each of said side walls having formed therein a plurality of obliquely and downwardly extending openings, and each of said bottom walls having formed therein a plurality of obliquely and upwardly extending openings.

8. In a conveyor, conveying means, a trough section intermediate said conveying means and having side and bottom walls each formed with a plurality of corrugations, there being discharge openings formed in said corrugations, and means for supplying cooling water to said openings, the corrugations and openings being so arranged that the corrugations in the side walls lie in the path of discharge from the openings in the corrugations of the bottom wall.

9. In a conveyor, conveying means, a trough section cooperating with said conveying means and comprising hollow side and bottom walls, and means for supplying water to said hollow side and bottom walls, said bottom walls being formed with a plurality of openings inclined toward said side walls so that the water discharged therefrom will impinge against the side walls when unopposed by material on a conveyor.

10. The combination with a conveyor comprising a longitudinally extending hollow girder, having a water inlet and a water outlet, of conveying rolls journaled in said girder, and a hollow trough carried by said girder intermediate said conveying rolls and having an inlet opening alining with the outlet opening in said girder.

40 In testimony whereof I have hereunto set my hand.

GUSTAF L. FISK.
